UNITED STATES PATENT OFFICE.

ALEXANDER WINTON AND HAROLD B. ANDERSON, OF CLEVELAND, OHIO, ASSIGNEES TO
THE WINTON MOTOR CARRIAGE COMPANY, OF CLEVELAND, OHIO.

CARBURETER.

No. 926,533.

Specification of Letters Patent.

Patented June 29, 1909.

Application filed March 9, 1907. Serial No. 361,543.

To all whom it may concern:

Be it known that we, ALEXANDER WINTON and HAROLD B. ANDERSON, citizens of the United States, residing at Cleveland, in the county of Cuyahoga and State of Ohio, have invented certain new and useful Improvements in Carbureters, of which the following is a specification, reference being had therein to the accompanying drawing.

10 This invention relates to improvements in carbureters, and is for use in connection with explosive motors for the purpose of furnishing a uniform explosive mixture to motors of different types and involves the principle of 15 operation wherein a body of fluid is maintained within the air passage for surface carburization of slowly moving volumes of air, and to effect a spray carburization of the rapidly moving volumes of air.

20 In those types of motors which limit the movement of the inlet valves and cause them to act as a throttle for controlling the speed and power of the engine, the air passing to the motor even at its lowest speed passes 25 through the carbureter in pulsating waves, whereas in that type of motor having a throttle in the passage-way between the carbureter and the engine, and in which the inlet valves are mechanically opened wide, the intervening 30 throttle causes the air to pass through the carbureter when the engine is running slow, at low though constant velocities, and more difficulty is encountered in causing the slow but constantly moving volumes of air to be properly carbureted by surface carburization.

35 The object of the present invention is to construct a carbureter of the type hereinbefore mentioned which is so constructed that the air which is moving in slow but constant 40 velocities is caused to travel in contact with the exposed body of volatile fluid and thereby cause it to be properly carbureted for slow speeds of the second type of motors, as well as the first type.

45 Referring now to the drawings, Figure 1, is a view of the carbureter embodying the present improvement with the air passage shown in longitudinal section. Fig. 2, is an edge 50 view of the movable or swinging deflector for the air passage. Fig. 3, is an edge view of the deflector.

55 Referring now to the drawings, 1 is a fluid chamber for the gasoline, and in which the fluid is maintained at a predetermined level

in any of the well known ways, which need not be here described, to enable this improvement to be understood. The gasoline is maintained at the level indicated and marked in Fig. 1 by dotted line, and the words "Fluid level". From this it will be seen that the maintained level of the chamber 2 is such that the fluid will flow by gravity through the passage-way 2 into the air passage 3, and a body of fluid maintained within this air passage. The rapidity with which the liquid will flow through the opening 2 in the operation of the carbureter may be regulated by a valve 4.

This carbureter is designed more particularly for use in connection with that type of motors having a throttle located in the passage between the carbureter and the engine at any desired point. For illustrative purposes it is here shown adjacent the outlet end of the passage 3, as indicated at 12. As previously stated, in this class of motors the air passes through the carbureter at constant velocities, and more especially is this true when the throttle 5 is nearly closed for the purpose of causing the engine to run slow.

For the purpose of causing the volumes of air which move through the passage-way at slow, but constant velocities to be properly carbureted by surface exposure of the fluid thereto, a deflector 6 is placed in this passage-way, and this deflector is arranged to be moved by the influence of the air passing through the passage-way, when its velocity is sufficient to move it. While this deflector 90 may be arranged in many ways, the form selected for illustrating the principle herein disclosed is a swinging deflector having its upper end loosely pivoted at the point 7 which is located at the upper wall of the passage 3. This deflector is declined in the direction of the travel of the air through the passage 3, whereby the air, when it has reached a sufficient velocity, will have a tendency to lift it. As shown, this deflector 100 is placed with its lower and free end adjacent the oil outlet 2, and is provided with a cut-away portion to form a passage-way 8 directly at the point of oil exposure. The operation of this deflector, is to cause the 105 slowly but constantly moving volumes of air to pass through the passage 8, and in direct contact with the body of surface exposed fluid. The deflector is made in the form here shown of a weight to maintain the posi- 110

tion shown in Fig. 1, when the engine is running at its minimum speed, and thus cause all of the air to pass adjacent and in contact with the surface exposed fluid, and to pick up and cause a proper carburization thereof.

The opening in the deflector is of a size to allow a sufficient air to pass therethrough when in the position shown in Fig. 1 for the very lowest motor speed, as when the motor is not under load, and the deflector is of a weight sufficient to maintain this position with the air passing through at its lowest velocities. In this form, the proper size of the opening and the weight of the deflector are fixed quantities for a motor of a given bore and stroke. To add to the weight of the deflector, and to facilitate the adjustment of its weight by removing a portion thereof, it is provided with the longitudinal ribs 9, it being made in the first place of a weight which may possibly require some lightening, though it will be understood that the proper weight of deflector having been once determined for a motor of a given size, by careful manufacture it could be duplicated and thus prevent the necessity of adding to or taking therefrom. When the throttle is open sufficiently to require more air than can pass through the cut-away portion 8, the deflector will be raised sufficiently to permit this increased volume of air to flow through the passage 3, and when the volumes of air passing through the passage 3 are of such quantity that they require more gasoline than is furnished by the exposed surface, or in other words, pick up or absorb more oil than flows through the opening 2 to the passage 3, then the carbureter becomes a jet carbureter and the passing air is carbureted by spray action.

By the arrangement and construction herein shown and described, a proper carburization of the slowly moving volumes of air is insured, while an excessive carburization of the rapidly moving volumes of air is prevented, and a uniform mixture obtained for the various speeds of the motor.

We desire it to be understood that other forms of deflectors could be devised without departing from the scope of this present invention when having the teachings of this disclosure at hand, and we do not therefore limit ourselves to the specific form here shown.

In the form of deflector here shown, the air

passage is made rectangular at the point 55 where the deflector is located, and the deflector will fit it sufficiently snug to prevent any appreciable passage of air past its sides. To enable the insertion and removal of the deflector, the passage is provided with an opening 10 and a removable cover 11 therefor.

A valve or throttle 12 is located in the outlet end or portion of the air passage, which when partially closed, causes the air to pass 65 the oil inlet relatively slow, and the deflector restricts the air passage and causes these slowly-moving volumes of air to pass close to the oil inlet 2.

Having thus described this invention, 70 what is claimed and desired to be secured by Letters Patent, is:—

1. A carbureter having an air passage, a fluid inlet therein means adapted to maintain a body of volatile fluid therein for surface carburization of slowly moving volumes of air and the fluid inlet restricted to cause spray carburization of rapidly moving volumes of air, and a movable air deflector within the air passage-way adapted to direct 75 the slowly moving volumes of air downward against the said maintained body of fluid, and to be lifted by the rapidly movable volumes of air for spray carburization thereof.

2. A carbureter having an air passage provided with a fluid inlet in its bottom, means for maintaining a body of volatile fluid therethrough in the bottom of the passage by gravity flow for surface carburization of slowly moving volumes of air, the inlet so 90 restricted as to require suction of the fluid through the inlet for spray carburization of the rapidly-moving volumes of air, a deflector within the air passage and freely movable in the direction of the air through the 95 passage, said deflector having an opening adjacent the body of fluid for the slowly-moving volumes of air, and adapted to swing open under the influence of the rapidly-moving volumes of air.

In testimony whereof we affix our signatures in presence of two witnesses.

ALEXANDER WINTON.
HAROLD B. ANDERSON.
